UNITED STATES PATENT OFFICE.

HERRMAN ENGE, OF WEST BERKELEY, CALIFORNIA.

PROPELLER.

SPECIFICATION forming part of Letters Patent No. 769,256, dated September 6, 1904.

Application filed June 17, 1903. Serial No. 161,797. (No model.)

To all whom it may concern:

Be it known that I, HERRMAN ENGE, a citizen of the United States, residing at West Berkeley, Alameda county, State of California, have 5 invented certain new and useful Improvements in Propellers; and I do hereby declare the following to be a full, clear, and exact description of the same.

The present invention relates more particularly to propellers designed for small boats, such as launches driven by gasolene or steam, and resides in the means whereby the propeller-blades may be shifted to change the boat's speed or the direction of its travel without reducing the speed of its drive-shaft or changing the direction of its rotation, thus dispensing with the complicated and expensive mechanism required to reverse the boat's direction of travel and vary its speed.

20 By the use of the hereinafter-described propeller the speed of the boat may be quickly varied and its direction of travel changed or reversed while the drive mechanism is operating under full head.

25 To comprehend the invention reference should be had to the accompanying sheet of drawings, wherein—

Figure 1 is a rear end view of the propeller, the hub-cap being removed in order to illustrate the connection between the operating-rod and the crank-arms for the propeller-blades. Fig. 2 is a longitudinal sectional plan view of the hub, illustrating the position of one of the crank-arms when the blades are 35 positioned as set forth in Fig. 1 of the drawings. Fig. 3 is a similar view of the hub with the parts positioned to place the propeller-blades in a vertical or non-operative position. Fig. 4 is a similar view disclosing the position 40 of one of the crank-arms when the propeller-blades stand in a reverse position to that illustrated by Figs. 1 and 2 of the drawings, and Fig. 5 is a detail broken perspective view of the operating-shaft and its head for engaging 45 with and actuating the crank-arms of the propeller-blades during longitudinal movement of the operating-rod.

The numeral 1 is used to indicate a propeller-shaft, to the outer end of which is attached 50 the hub 2. Through the propeller-shaft 1

works longitudinally the rod 3, which rod is moved inward and outward by any suitable mechanism. This rod works through the hub 2, its outer end resting within the bearing 4 of the cap 5 for the outer end of the said hub. 55 To this rod within the chamber 6 of the hub 2 is secured a triangular head 7, which head is provided with a series of pairs of projecting studs 8 9. These studs alternately engage with the radial slots or sockets 10 11, cut in 60 the outer edge portion of the crank-arms 12. There is a crank-arm 12 for each propeller-blade 13, which crank-arms are attached by set-screws 15' to the shank 15 of the propeller-blades. Said shanks 15 extend through the 65 outer wall of the hub 2, the crank-arms being attached to the ends projecting within the chamber 6 of the said hub. The position of the crank-arms 12 controls that of the propeller-blades 13, the throw of the crank-arms in 70 turn being regulated through their connection with the head 7 by the movement of the rod 3.

Presuming the parts to stand in the position set forth in Fig. 2 of the drawings, which 75 positions the propeller-blades 13 at an inclination for forward travel of a boat, and it is desired to place the propeller-blade in a vertical or neutral position, the operating-rod 3 is then moved or forced outward, causing the 80 studs or pins 8 of the head 7 to gradually move from within seat 10 of the crank-arms 12 and studs or pins 9 of each pair to work within the seats 11, so as to gradually force or turn the crank-arm 12 during the outward movement of rod 3 to throw the propeller-blade 85 from the position indicated by dotted line *a*, Fig. 2 of the drawings, into the position indicated by dotted line *b*, Fig. 3 of the drawings. To change the position of the propeller-blades 13 from that set forth in Fig. 1 of the drawings to a position such as will during rotation of the propeller impart a reverse movement to the boat's travel, the operating-rod 3 is forced or drawn inward. This movement 90 of the rod causes the studs or pins 9 to gradually move from within the seats 11 of the crank-arms 12 and the pins or studs 8 to gradually enter within the seats 10 of the said 95 crank-arms. The result is to gradually turn 100

the crank-arms 12 with the movement of the operating-rod 3 and to throw the blades 13 into a position or at an inclination indicated by dotted line α , Fig. 4 of the drawings.

5 It will be understood that the described changes as to the position of the propeller-blades are made without requiring the movement or rotation of the propeller-shaft 1 to be stopped, inasmuch as the rod 3 is actuated 10 independent of the propeller-shaft 1.

It will be observed that the means employed for shifting the propeller-blades are entirely inclosed or housed within the propeller-hub 2, being thus protected from contacting with 15 and becoming clogged or choked by seaweed or floating substances, which would occur in case the actuating means worked from the outside of the said hub 2.

As each crank or crank-arm 12 is secured to 20 a propeller-shank 15, the propeller-blades 13 of necessity must shift with the throw of the cranks 12 as actuated by the longitudinal movement of the operating-rod 3.

As stated, the invention is mainly designed 25 for propellers used in connection with the

driving of small-size boats, the object being to enable the boat's speed to be quickly varied or its direction of travel changed without disturbing the operation or movement of the drive mechanism for the propeller.

Having thus described the invention, what is claimed as new, and desired to be protected by Letters Patent, is—

30 A propeller comprising a hub, a series of propeller-blades rotatably secured therein, a series of cranks located within the hub and connected to the shank of each blade, a pair of seats cut in each crank, a longitudinally-movable rod working through the hub, and a series of projecting studs carried by said 40 rod, said studs engaging with the seats of the cranks so as to operate the said cranks to shift the blades during longitudinal movement of the rod.

In witness whereof I have hereunto set my 45 hand.

HERRMAN ENGE.
